UNITED STATES PATENT OFFICE.

ELMER H. RECORDS, OF SPOKANE, WASHINGTON.

LIQUID FUEL.

No Drawing.

Application filed January 6, 1925. Serial No. 878.

My present invention relates to an improved liquid fuel for use as a motive fluid or source of power in internal combustion engines for automotive vehicles. The primary object of the invention is the provision of a fuel containing alcohol as a base or carrier and ingredients blended therewith for the purpose of increasing the explosive power of the fuel charge and at the same time reduce the cost of production of the liquid fuel.

In carrying out my invention I produce a highly combustible liquid mixture for a fuel which maintains itself in a non-separable, permanent, non-stratifying and stable liquid solution, ready at all times for use.

The fuel is highly volatile and easily carbureted in standard carbureting systems of internal combustion engines, and possesses an exceedingly high and quick explosive power at a comparatively low temperature—lower than that usually required for gasoline and other liquid fuels.

By exploding the fuel charge at a materially lower temperature than that of such a fuel as gasoline, the engine is subjected to a lower degree of heat generated by the explosions in the cylinders of the motor, thus operating the engine under more favorable conditions for the necessary efficiency.

In the accompanying specification and claim I have set forth an example of the chemical formula of the fuel composition of my invention wherein a base of low proof alcohol is used and the necessary ingredients chemically combined and blended therewith.

I have found by actual tests and practical and extended use that the following formula provides an excellent fuel for the purpose:

	Per cent.
Alcohol	72
Benzol	18
Ether	5
Naphthol	2.50
Oxygen (ozone or hydrogen peroxide)	1.50
Sodium hydroxide	1.00

These component parts in the proportions indicated by volume are thoroughly commingled, blended and mixed in suitable vessels to form a soluble mixture which provides a liquid fuel of high carbon content

that possesses a quick explosive power and ready flash point with a low burning point. 55

Oxygen used in the mixture, ozone or hydrogen peroxide, when released under combustion, supplies an added factor or fresh substance for consumption under expanding conditions of the fuel charge in the 60 cylinder, to increase the power of the explosion in the engine.

The use of the sodium hydroxide in the mixture renders it of an alkaline nature 65 possessing the property of preventing rust and at the same time assisting in the lubricating factors of the fuel. The anti-rust feature of the mixture prolongs the durability of the tanks and pipes in the fuel feeding system by eliminating possibility of rust 70 therein.

In the preferred form or method of manufacturing the liquid fuel I find it desirable that a fractionating still be used for the alcohol, in order that ethyl ether which 75 may be drawn off with facility, may be collected and later used as a distillate by adding to the mixture. I find by actual practice that fermented mash accruing in the manufacture of alcohol contains approximately 16% alcohol, also contains considerable ethyl ether.

Of this recovery through the fractionating still, a sufficient quantity of ether will be on hand at all times in the manufacture 85 of alcohol, for providing a source of supply of ether for the fuel. The production of this ethyl ether is thus comparatively inexpensive, and its use fills the requirements of, and at the same time eliminates the necessity 90 for a larger quantity of the more expensive benzol. In some instances ethyl ether recovered in the distillation of alcohol with sulphuric acid may be used.

In actual practice and by extended use I 95 have demonstrated that a liquid fuel solution made according to this formula, when used in an internal combustion engine, gives an increased power and mileage in volume of fluid, to a material degree, over that of 100 gasoline as a fuel. Under these conditions I have found that the heat generated by combustion is greatly reduced, and consequently the engine structure is subjected to a less degree of heat than is usual in gasoline engines, and the motor is thus permitted to 105

operate under more favorable conditions and with greater efficiency. While running under these more favorable conditions the necessity for cooling mediums for the engine 5 is lessened to a considerable degree.

The liquid fuel thus produced, I find is superior in many respects to gasoline; the fuel may be economically produced, and is free from most objectionable features inherent in fuel mixtures heretofore used as substitutes for gasoline as a liquid fuel. 10

Having thus fully described my invention

what I claim as new and desire to secure by Letters Patent is:

A fuel comprising by volume

	Per cent.	16
Alcohol	72	
Benzol	18	
Ether	5	
Naphthol	2.50	20
Hydrogen peroxide	1.50	
Sodium hydroxide	1.00	

In testimony whereof I affix my signature.
